CLAIM

The ornamental design for a stake hole maker, as shown and described.

DESCRIPTION

FIG. 1 is a side elevation view of the two part stake hole maker comprising a KEY member and a hole maker member shown in side-by-side relationship.

FIG. 2 is a front elevation view of the two part stake hole maker illustrating the KEY member and the hole maker member shown in side-by-side relationship.

FIG. 3 is a rear elevation view of the two part stake hole maker illustrating the KEY member and the hole maker member shown in side-by-side relationship.

FIG. 4 is a top plan view of the two part stake hole maker illustrating the KEY member and the hole maker member shown in side-by-side relationship.

FIG. 5 is a bottom plan view of the two part stake hole maker illustrating the KEY member and the hole maker member shown in side-by-side relationship;

FIG. 6 is an isometric view of the two part stake hole maker illustrating the cooperating relationship of the KEY member and the hole maker member in separated side-by-side relationship; and,

FIG. 7 is an environmental perspective view of the two part stake hole maker with the KEY member cooperating with the hole maker member when used in driving the hole maker member into a surface where a hole is to be made and, in phantom, illustrating a mechanism for extracting the hole maker member from the surface after a stake hole has been created.

The broken line showing in FIG. 7 is included for the purpose of illustrating environmental structure and forms no part of the claimed design.

The stake hole maker is shown separated for ease of illustration in FIGS. 1-6.
